UNITED STATES PATENT OFFICE.

ANDREW DOWNEY, OF COLUMBUS, OHIO.

TOY.

1,162,687.

Specification of Letters Patent.

Patented Nov. 30, 1915.

Application filed February 24, 1915. Serial No. 10,222.

To all whom it may concern:

Be it known that I, ANDREW DOWNEY, a citizen of the United States, residing at Columbus, in the county of Franklin and State 5 of Ohio, have invented certain new and useful Improvements in Toys, of which the following is a specification.

My invention relates to toys and has particular bearing to those types of toys embodying loosely jointed objects such as men 10 and the like to enable them to gyrate freely under certain conditions.

The main object of my invention resides in the provision of a toy wherein exaggerated movements of pugilists or dancers 15 may be simulated. In this connection, I preferably provide a vibrating mechanism of some type in order that its vibrations may be imparted to the loosely jointed objects 20 to cause their component parts to oscillate.

The preferred embodiment of my invention is shown in the accompanying drawings, in which similar characters of reference designate corresponding parts, and in 25 which:

Figure 1 is a side view of my improved toy, Fig. 2 is a vertical section through the body portion of the structure shown in Fig. 1, Fig. 3 is a top plan view of the structure 30 shown in Fig. 2, and, Fig. 4 is a side view of the structure shown to the right of Fig. 1.

In these drawings, I have shown a pair of side plates designated 1 held spaced from each other and in assembled relation by 35 means of cross pieces 2. Between these side plates 1, I have suitably journaled a shaft 3 rigidly carrying a ratchet wheel 4, this ratchet wheel forming a portion of an escapement mechanism desirably used by me 0 to provide the necessary vibratory action. This ratchet wheel 4 is also provided with a 5 downwardly extending integral trigger formation 5 located in a manner convenient and within the range of movement of the forefinger of an operator when the device as a whole is gripped by means of the wires 6 bent to handle form, it being noted that these handles 6 are also rigidly attached to the side plates as is shown at 7. Cooperating with this rigid structure is a torsion spring shown at 8, one end of this spring 8 being attached to one of the cross pieces 2 while its opposite end 10 bears upon the trigger portion 5 in order to normally force the same in a forward direction. To complete the escapement structure, I have pro-

vided a lever 11 whose pallets 12 are designed to coöperate with the teeth on the ratchet 4 in the well known manner, this lever 11 being rigidly carried upon a shaft 60 13 in such manner that the lever itself is pivoted centrally. A forwardly extending rod 14 is rigidly attached at one end to the lever portion 11 of the escapement mechanism, while its forward end is provided 65 with a hook formation 15. This hook is designed to engage an eye 16 carried by a cross lever shown at 17, this eye 16 being in approximately the center of the cross lever and pivotally carrying a figure 18, preferably in the nature of a man, at each end. It will be noted that the portions of the figures to which the cross piece 17 is attached, pivotally carry the legs 19 and the arms 20.

The manner of operation of my device is as follows: The toy as a whole is grasped by the hand and the fore-finger is caused to embrace the trigger 5. As will be apparent the spring 8 normally forces the trigger 5 forwardly, it being limited in its forward movement by the engagement of one of the pallets 12 with the upper end of the trigger itself. Return movement by the pressure of the finger, causes the pallet 12 70 in engagement with one of the teeth of the ratchet wheel 4, to be moved out of engagement, while the other pallet naturally moves 75 into a position of engagement. Continued movement will then force this last engaging pallet out of engagement and the original pallet into engagement with one of the 80 teeth of the ratchet wheel and in this manner the free movement of the ratchet wheel 85 4 is retarded and at the same time a rapid 90 oscillation of the stem 14 is effected. In 95 this manner, the objects pivoted to the ends of the cross piece 17, are caused to vibrate and their pivoted portions will gyrate to simulate in an exaggerated manner the 100 movements of a pugilist or a dancer. These 105 movements are further enhanced by placing the pivoted portions 19 of the figures 18 in light engagement with a table top or other suitable object.

What I claim, is:

1. A toy comprising a handle, a vibrating mechanism including a trigger located adjacent said handle, a forwardly extending rod operatively connected at one end to said mechanism, and a loose jointed object carried by the other end of said rod.

2. A toy comprising a handle, an escapement mechanism, a trigger located adjacent said handle for operating said mechanism, a forwardly extending rod connected to said mechanism at one end, a cross rod carried by the other end of said forwardly extending rod, and a loose jointed object carried by each end of said cross rod.
3. A toy comprising a handle and framework, a ratchet wheel carried by said framework, a trigger rigidly carried by said wheel, spring means normally tending to rotate said wheel, an escapement lever coöperating with said ratchet, a forwardly extending rod connected to said lever at one end, a cross rod carried by the other end of said forwardly extending rod, and a loose jointed object carried by each end of said cross rod.
4. A toy comprising a handle, a suitable

framework, a ratchet wheel carried by said framework, a trigger integrally formed in connection with said ratchet wheel and normally disposed to extend downwardly to a position adjacent to said handle, spring means normally tending to rotate said wheel in one direction, an escapement lever coöperating with said ratchet, a forwardly extending rod connected at one end to said lever, a cross rod carried by the other end of said forwardly extending rod, and a loose jointed object carried by each end of said cross rod.

In testimony whereof I affix my signature in presence of two witnesses.

ANDREW DOWNEY.
